CLAIM

The ornamental design for a coaxial cable connector in open position, as shown and described.

DESCRIPTION

FIG. 1 is a rear perspective view of a coaxial cable connector in open position showing our new design;

FIG. 2 is a front perspective view thereof;

FIG. 3 is a top plan view thereof, the bottom being a mirror image;

FIG. 4 is a right side plan view thereof, the left side being a mirror image;

FIG. 5 is a front plan view thereof; and,

FIG. 6 is a rear plan view thereof.

The subject matter shown in broken lines is for illustrative purposes only and forms no part of the claimed design.
